CLAIM

The ornamental design for a wearable non-invasive analyte sensor, as shown and described.

DESCRIPTION

FIG. 1 is a perspective view of a wearable non-invasive analyte sensor according to my new design.

FIG. 2 is a top view thereof.

FIG. 3 is a bottom view thereof.

FIG. 4 is a left side view thereof.

FIG. 5 is a right side view thereof.

FIG. 6 is a front view thereof.

FIG. 7 is a rear view thereof; and,

FIG. 8 is another perspective view of a wearable non-invasive analyte sensor together with a portion of wrist strap for attaching the wearable non-invasive analyte sensor to one's wrist.

The broken lines in the drawings depict environmental subject matter only and form no part of the claimed design.
